US00D849665S

(12) **United States Design Patent** (10) **Patent No.:** **US D849,665 S**
Badillo (45) **Date of Patent:** **** May 28, 2019**

(54) **ROOF RACK INSERT**

(71) Applicant: **Intelligent Designs 2000 Corp.**,
Aurora, CO (US)

(72) Inventor: **Paul Badillo**, Littleton, CO (US)

(73) Assignee: **INTELLIGENT DESIGNS 2000
CORP.**, Aurora, CO (US)

(**) Term: **15 Years**

(21) Appl. No.: **29/612,929**

(22) Filed: **Aug. 4, 2017**

Related U.S. Application Data

(63) Continuation-in-part of application No. 29/535,957, filed on Aug. 12, 2015, now Pat. No. Des. 793,946, which is a continuation of application No. 13/942,489, filed on Jul. 15, 2013, now Pat. No. 9,676,343, which is a continuation of application No. 12/861,034, filed on Aug. 23, 2010, now Pat. No. 8,496,146.

(57) **CLAIM**

The ornamental design for a roof rack insert, as shown and described.

DESCRIPTION

FIG. 1 is a perspective view of a roof rack insert;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is a perspective view of the roof rack insert positioned adjacent to a vehicle roof rack;
FIG. 9 is a perspective view of a roof rack insert according to another embodiment;
FIG. 10 is a front elevation view of the roof rack insert of FIG. 9;
FIG. 11 is a rear elevation view of the roof rack insert of FIG. 9;
FIG. 12 is a left elevation view of the roof rack insert of FIG. 9;
FIG. 13 is a right elevation view of the roof rack insert of FIG. 9;
FIG. 14 is a top plan view of the roof rack insert of FIG. 9;
FIG. 15 is a bottom plan view of the roof rack insert of FIG. 9; and,
FIG. 16 is a perspective view of the roof rack insert of FIG. 9 positioned adjacent to a vehicle roof rack.
The broken lines depict unclaimed environmental subject matter and do not form any part of the claimed design.

1 Claim, 8 Drawing Sheets
